UNITED STATES PATENT OFFICE.

CHARLES C. SPREEN, OF DETROIT, MICHIGAN.

MECHANICAL REFRIGERATION.

Application filed June 4, 1926. Serial No. 113,665.

My invention relates to mechanical refrigeration, and particularly to refrigerating units for domestic refrigeration apparatus, and the principal object of my invention is to provide new and improved units of this type. In the drawings accompanying this specification and forming a part of this application I have shown, for purposes of illustration, several forms which my invention may assume. In these drawings:

Figure 1 is a front elevation showing one illustrative embodiment of my invention.

Figure 2 is a side elevation of the embodiment shown in Figure 1.

Figure 3 is a top plan view of the embodiment shown in Figures 1 and 2.

Figures 4 through 6 are views similar to Figure 2 showing three further embodiments of my invention, while

Figures 7 and 8 are views similar to Figure 3 showing two further embodiments which my invention may assume.

The embodiment of my invention shown in Figures 1 through 3 comprises a brine tank 11 supporting the usual expansion valve 12 and the usual end turns 13 carrying the thermostat 14, containing within itself an expansion coil (not shown) connected between the expansion valve 12 and the end turns 13, and provided with recesses 15 extending in from the front face thereof and arranged to accommodate receptacles 16 for the formation of artificial ice under the action of the refrigerating unit.

It is well known to those skilled in the art that during the operation of a refrigerating unit of this type frost gradually accumulates on the exterior surface of the brine tank 11, that this accumulation of frost continually decreases the rate of absorption of heat from the refrigerator cabinet into the refrigerating unit, and that periodic defrosting of the refrigerating unit is ordinarily required.

In order to lengthen the period during which a refrigerating unit will operate satisfactorily without defrosting, or perhaps to eliminate entirely the necessity for any defrosting, and in order to at all times greatly increase the rate of heat absorption from the refrigerator cabinet into the refrigerating unit, I provide on each side face 17 of the brine tank 11 a plurality of fins 18 convoluted to provide additional length, extending generally vertically in order not to prevent the dropping from the refrigerating unit by gravity of frost which may become dislodged

or melted, and projecting from the brine tank 11 a distance greater than the thickness to which the frost will accumulate on the brine tank 11 under normal operation of the refrigerating unit.

The embodiment of my invention shown in Figure 4 comprises a brine tank 19 again supporting the usual expansion valve 20 and the usual end turns 21 carrying the thermostat 22, again containing an expansion coil (not shown) extending between the expansion valve 20 and end turns 21, but omitting the recesses 15 for the ice receptacles 16, and accordingly provided with fins 23 on all four lateral faces, the fins 23 having a different convolution from the fins 18 of the embodiment of my invention shown in Figures 1 through 3 but being convoluted, extending generally vertically in order to again not prevent the dropping by gravity of frost which may become dislodged, and again projecting from the brine tank a distance greater than the thickness to which the frost will accumulate under normal operation of the refrigerating unit.

The embodiments of my invention shown in Figures 5 and 6 are in all respects similar to the embodiment shown in Figure 4 except that they substitute for the zig-zag fins 23 of the embodiment shown in Figure 4 diagonal fins 24 and vertical fins 25, respectively.

The embodiment of my invention shown in Figure 7 comprises a brine tank 26 again supporting the usual expansion valve 27 and the usual end turns 28 carrying the thermostat 29, containing an expansion coil (not shown) extending between the expansion valve 27 and the end turns 28, provided with recesses (not shown) similar to those provided in the embodiment of my invention shown in Figures 1 through 3, and provided on its side walls 30 with fins replacing the fins 18 of the embodiment of my invention shown in Figures 1 through 3 but formed from a single sheet of material 31 arranged in loops 32 disposed on the side faces 30 of the brine tank 26 and alternated with base portions 33 in contact with the side faces 30 of the brine tank 26 and affixed to the side faces 30 of the brine tank 26 in any suitable manner, as by welding or soldering, the loops 32 extending vertically in order not to prevent dropping by gravity of any dislodged frost, and projecting from the brine tank 26 a distance greater than the thickness

to which the frost forms under normal operation of the refrigerating unit.

The embodiment of my invention disclosed in Figure 8 is in all respects similar to that shown in Figure 7 except that it substitutes for the rounded loops 32 of the embodiment shown in Figure 7 pointed loops 35 acting in the same general manner as the rounded loops 32 of the embodiment shown in Figure 7.

It will be understood, of course, that the types of fins shown in the embodiment of Figures 1 through 3 and in the embodiments of Figures 7 and 8 may be used with a refrigerating unit of the type shown in Figures 4 through 6, and that fins of the types shown in Figures 4 through 6 may be used with refrigerating units of the type shown in Figures 1 through 3 and in Figures 7 and 8.

From the above description it will also be obvious to those skilled in the art that I have provided new and improved refrigerating units particularly suitable for domestic mechanical refrigeration. At the same time it will also be obvious to those skilled in the art that the particular embodiments of my

invention herein shown and described may be variously changed and modified without departing from the spirit of my invention or sacrificing the advantages thereof and it will therefore be understood that the disclosure herein is illustrative only and that my invention is not limited thereto.

I claim:

For use in connection with a supply of compressed refrigerant, and in a refrigerator cabinet, and for cooling such cabinet, and under conditions which normally cause the accumulation of frost on the exterior of the brine tank thereof, a cooling unit comprising: such brine tank, a refrigerant expansion chamber within said brine tank, and a plurality of fins disposed on at least one of the exterior walls of said brine tank and extending outwardly therefrom a distance greater than the thickness to which such frost accumulates under normal operating conditions.

In testimony whereof I hereunto affix my signature.

CHARLES C. SPREEN.
